UNITED STATES PATENT OFFICE.

JESSE H. BUNNELL, OF BROOKLYN, NEW YORK.

ELECTRIC-SWITCH PLUG.

SPECIFICATION forming part of Letters Patent No. 325,653, dated September 8, 1885.

Application filed November 13, 1884. (No model.)

To all whom it may concern:

Be it known that I, JESSE H. BUNNELL, a citizen of the United States, residing in Brooklyn, in the county of Kings and State of New York, have invented certain new and useful 5 Improvements in Electric-Switch Plugs, of which the following is a specification.

My invention relates to certain improvements in the mode of attachment of flexible 10 conductors to the movable wedges or plugs of a telegraphic or electric switch-board; and its object is to avoid liability of said flexible conductors being broken by reason of frequent handling, at or near their point of attachment 15 to the wedge or plug. I effect this by providing the insulating-handle of the plug with a projection, which projection is preferably provided with grooves or channels for receiving the ends of the flexible conducting-wires, and 20 with a flexible sleeve of india-rubber or other like material, which fits over the grooved or channeled projection and the ends of the flexible cord or conductor, and thus serves to protect the same from accident or injury.

25 In the accompanying drawings, Figure 1 is a front elevation of my improved switch-plug with the movable sleeve slipped down so as to exhibit the manner of attachment of the ends of the flexible conductor. Fig. 2 shows 30 the device when in its proper position for use, and Fig. 3 is a transverse section in the plane of the dotted line 3 3 in Fig. 2.

In the drawings, A represents one of the 35 metallic face-plates or terminals upon the body B of the switch-plug. The latter is formed of hard rubber or other suitable material, and is enlarged at b in the ordinary manner, as shown, so as to form a convenient handle.

D is a flexible insulated cord containing 40 wires or conductors c c', which are properly insulated from each other, and covered with woven or braided material in a well-known manner, as shown. One of these conductors, c, passes through a hole in the handle b of the

45 plug B and along the groove C to the metallic terminal A. The other wire, c', is conducted in like manner through another groove on the back side of the plug B to another similar metallic terminal in the rear of A.

Heretofore it has been usual to pass the 50 wires c c' directly from the upper end of the woven flexible cord D into and through the holes in the handle b to the terminals A; but this mode of construction has rendered the conductors extremely liable to breakage from 55 being frequently bent back and forth just at the point of their insertion into the handle b. In order to obviate this objection I provide the handle b with a projection, B', preferably forming an integral part thereof, which is furnished with grooves or recesses on each side, 60 as shown at d d in Fig. 3. Through these recesses the conductors c and c' are carried, and secured in place by a suitable binding, e. A tube or sleeve, E, of some durable and flexible 65 material—such as india-rubber—is then slipped over the joint, as shown in Figs. 2 and 3. This inclosing-sleeve serves to effectually protect the parts, and to support the conductors at the point of flexure, so that they are not 70 liable to become injured by frequent and continuous use, and at the same time renders them convenient of access for inspection or repairs.

I claim as my invention—

The combination, with the wedge or plug 75 of an electric switch-board, of a projection upon the handle of said wedge or plug for receiving the conducting-wires, and a flexible tubular sleeve for inclosing said projection and protecting said wires, as set forth. 80

In testimony whereof I have hereunto subscribed my name this 12th day of November, A. D. 1884.

JESSE H. BUNNELL.
